AUTOMATIC LOCK

Albert J. Leonard, Los Angeles, Calif.

Application November 30, 1945, Serial No. 631,943

18 Claims. (Cl. 70—208)

1

This invention relates generally to the art of locks and latches, and more particularly to locks of the type embodying a handle movable from an operating position wherein it is accessible for manipulation to open the closure with which it is associated, to a non-operating position wherein the handle may be substantially flush with the exterior surface of the closure.

An object of this invention is to provide a lock of the above described character, which, in association with the door of an automobile, for example, is automatically operable in response to closing of the door, to move the outside door handle from its operating position wherein it projects from the door for manipulation, to a non-operating position wherein the handle will be substantially flush with the exterior surface of the door, thus adding to the safety and security of the vehicle by preventing unauthorized persons from tampering with the handle and possibly breaking off same in an effort to force the lock; adding to the safety of operation of the vehicle by eliminating dangerous projecting handles which have been the cause of many accidents; and enhancing the streamlined appearance of the vehicle.

A further object of this invention is to provide an automatically operable locking mechanism as above set forth, whose handle may be manually released from its non-operating position and restored to its operating position either in response to a manual operation of an actuator on the outside of the door, when the door is unlocked, or by manipulation of a handle on the inside of the door.

Still another object of this invention is to provide a lock whose compact and ingenious construction enables it to be installed in doors of the most modern automobiles projected for future manufacture, the door frames of which are intended to be extremely narrow to provide vertically sliding windows of maximum width for increased visibility between the hinge and lock stiles of the door, all while retaining the essential qualities of durability, freedom from maintenance, and simplicity of installation by standard manufacturing practice.

With these and other objects in view, the invention resides in the combinations, arrangements and functional relationships of elements as set forth in the following specification and particularly pointed out in the appended claims.

In the accompanying drawings,

Figure 1 is a view partly in side elevation and partly in section, of an automobile door and

2

jamb, with one form of automatic locking mechanism embodying this invention installed therein;

Figure 2 is a plan sectional view taken on the line 2—2 of Figure 1, and showing the door fully closed;

Figure 3 is a view similar to Figure 2 and showing the door partly open;

Figure 4 is an enlarged vertical transverse sectional view taken on the line 4—4 of Figure 1, and showing the outside handle in operating position, and the other working parts in the positions they occupy when the door is open;

Figure 5 is a vertical longitudinal sectional view taken on the line 5—5 of Figure 4;

Figures 6 and 7 are detail sectional views taken on the lines 6—6 and 7—7 of Figure 5, respectively;

Figure 8 is a fragmentary vertical sectional view taken on the line 8—8 of Figure 5, and showing the outside handle moved to non-operating position;

Figure 9 is a view similar to Figure 8 and showing the final position of the parts in the fully closed position of the door, and following movement of the outside handle to non-operating position; and

Figure 10 is a fragmentary bottom plan sectional view taken on the line 10—10 of Figure 9.

Referring specifically to the drawings, the invention in its illustrated embodiment is shown installed in a hollow sheet metal door D of the type employed on the most modern pleasure automobile bodies, which is suitably hinged along one vertical edge at H to the jamb J for opening and closing movements and for co-action of its bolt B with a keeper K on the jamb, it being understood that the usual vertically sliding window indicated at W in broken lines in Figures 2 and 3 is of increased width in accordance with the relatively narrow lock and hinge stiles of the door frame, all to the end of providing maximum window area for increased visibility from the interior of the body.

For the purpose of this invention the bolt B has a pin-and-slot mounting 10 on a support in the form of a U-shaped sheet metal frame 11 secured in the door D at the lock stile thereof, the bolt projecting through registering openings in the frame 11 and the door for co-action with the connection 10 in mounting the bolt for reciprocating movement to engage and disengage the keeper K when the door is closed. A flat coil spring 12 is secured at one end to the bolt B as indicated at 13, and bears at its other end

against a lug 14 on one end of an S-shaped lever 15 mounted intermediate its ends for pivotal movement about a fixed axis on the frame 11, formed by a pin 16, all in such manner that the spring 12 is adapted to urge the bolt to its projected or latching position shown in the drawings, as will be later fully apparent.

An inside handle 1 is fixed to a shaft 17 mounted in an L-shaped bracket 18 secured to the door D at the hinge stile thereof, and fixed to the shaft is an arm 19 having a pin 20 working in a slot 21 in one end of the link 22, the other end of which has a slot 23 in which works a pin 24 on the bolt B as clearly shown in Figure 1. A spring 25 normally urges the arm 19 to the position shown in this figure, for movement of the bolt B by the handle 1 to the retracted or non-latching position of the bolt.

An operating member or outside bar handle O of streamline contour has fixed thereto by screws 30, a hollow shaft 31 which projects through an opening 32 in a handle-receiving recess 33 formed in the outside wall 34 of the door D, the shaft being supported by a bearing 35, fixed to the frame 11 by screws 36. By means of the bearing 35, the shaft 31 is mounted for rotational and axial movement, and is normally urged axially by a coil spring 37 to its one extreme or operating position shown in Figures 3 and 4, wherein the handle projects from the recess 33 so as to be accessible for manipulation.

The coil spring 37 is mounted on a stem 40 rotatably mounted at one end in the frame 11 and projecting into the shaft 31 to which it is operatively connected by a diametric pin 41 in the shaft passing through a longitudinal slot 42 in the stem for co-action therewith in providing a rotatable driving connection between the handle and stem, yet permitting axial movement of the handle independently of the stem from the operating position of the handle shown in Figure 3, to the non-operating position of the handle shown in Figure 2, in which latter position the handle is disposed in the recess 33 so as to be substantially flush with the exterior surface of the outside door wall 34.

Fixed to the stem 40 by a pin 43 is an arm 44 adapted to engage one side of a lug 45 on the other end of the lever 15. Pivoted at 46 on the lever 15 is a connector lever 47 having a toe 48 seating in a recess 49 in the bolt B. Turning movement of the handle O in a clockwise direction as viewed in Figure 1 will cause the arm 44 to rock the lever 15 about the pin 16 and push upon the connector lever 47 through its pivot 46, for co-action of its toe 48 with the recess 49 in moving the bolt B to its retracted or non-latching position against the action of the spring 12. Thus, it will be evident that the bolt can be retracted by either the inside handle 1 or outside handle O independently of each other.

Adjacent the opening 32, the outside wall 34 is provided with an opening receiving a cylindrical shell 50 having an escutcheon flange 51 and fitting into a cup-shaped cylindrical casing 52 fixed to the frame 11. Axially movable in the shell 50 is a manual actuator 53 in the form of a ring having longitudinal slots 54 receiving lugs 55 on a cylindrical support 56 in which is fixed the body of a cylinder lock 57.

Screws 58 pass through the casing 52 and shell 50, and are threaded into the lugs 55 to rigidly secure the support 56 and hence the lock body to the casing. A stop plate 53a has a force fit in the actuator 53 and is engaged by a spring 59

which normally urges the actuator axially to the extreme position shown in the drawings and wherein the actuator projects a short distance from the wall 34 for movement inwardly against the action of the spring, by pressure of the fingers exerted against the actuator. The stop plate 53a has an eccentric slot 60 which, in the unlocked position of the lock 57, is alined with the locking lug 61 on the rotary barrel of the lock 57, so as to permit the actuator to be pushed inwardly from its outer extreme position shown in the drawings, to an inner extreme position wherein the lug 61 has been received in the slot 60. However, in the locked position of the lock 57, the locking lug 61 is rotated out of alinement with the slot 60, so that the lug 61 will co-act with the plate 53a to lock the actuator in its outer extreme position.

Mounted intermediate their ends on a pin 65 projecting from the frame 11 are two crossed and pivoted locking members or dogs 66 and 66a urged relatively in opposite directions about the pin by a spring 67, to yieldingly maintain the dogs at one end in engagement with cams 68 (Figure 7) 25 in the shape of oppositely extending oblique surfaces projecting into a slot 69 formed in the actuator 53, the dogs projecting freely through registering slots in the casing 52 and shell 50.

At their other ends, the dogs 66 and 66a are curved towards each other and pass freely through slots 70 in the bearing 35, and are adapted to ride on the periphery of the shaft 31 during axial movement of the latter in moving the handle O from its operating position shown in Figures 2 and 4, to its non-operating position shown in Figure 3, and to snap into an annular groove 71 in the shaft 31 under the action of the spring 67, when the handle reaches its non-operating position.

The inner end of the shaft 31 is provided with diametrically opposed radial shoulders 73 adapted to be engaged by the spaced parallel arms 74 of a shifting member or yoke 75, the hub 76 of which is freely mounted on a pin 77 supported in a generally U-shaped bracket 78 fixed to the frame 11. A spring 79 connected to a depending portion 80 of the bracket 78 and to an extension 81 of the shifting member 75 urges the latter to the extreme position shown in Figures 4 and 9, wherein one of the arms 74 of the member abuts a stop 82 on the bracket 78 (Figure 9).

Projecting from the hub 76 of the member 75 is a latching arm 83 having a notch 84 in which is adapted to seat the bill 85 of a connector or pawl 86 pivotally mounted intermediate its ends on a pin 87 spanning and supported by the parallel arms of a generally H-shaped member 88 also freely mounted on the pin 77 between the sides of the bracket 78 and the hub 76 of the shifting member 75. A suitable spring 90 secured to the cross arm of the member 88 and to the other rounded end of the connector 86, urges the latter in a direction for the bill 85 to enter the notch 84 in the latching arm 83, and for the rounded end 91 to engage the dwell and active portions 92 and 93, respectively, of a disconnector in the form of a cam fixed to the bracket 78, all for a purpose to be later fully described, the disconnector being designated generally by 94.

Connected to the pin 77 is one part of a two-part universal link 95, the other part of which is connected to one arm of a bell crank lever 96, pivotally mounted at 97 on the frame 11. The other arm of the lever 96 has a pin-and-slot connection 98 with one end of a push rod 99 constit-

tuting a door-controlled actuator, and reciprocably mounted in bearings 100 on the frame 11. The other end of the rod is mounted in the bracket 18 and projects through the frame of the door D, with the outer end of the rod having a head 101. A spring 102 mounted on the rod between one of the bearings 100 and a shoulder 103 on the rod, urges the rod, and hence the lever 96, link 95, member 88 and the connector 86 carried thereby, to the extreme position shown in Figures 3 and 4 wherein the head 101 projects from the hinge edge of the door D for engagement with an abutment plate 104 in the jamb J of the door in the operation of the invention which is as follows:

Let it be assumed that the door D is open; that the outside handle O is in operating position; and that the lock 57 is unlocked as illustrated in Figures 3 and 4, respectively. As the bill 85 of the connector 86 is seated in the notch 84 of the latching arm 85 in this position of the working parts, as shown in broken lines in Figure 4, closing movement of the door from the position shown in Figure 3 will cause the push rod 99 to strike the abutment plate 104 and be moved to the left as the door-closing movement progresses. This movement of the push rod will actuate the bell crank lever 96 in a direction for the latter to exert a pull upon the link 95 and cause the latter to swing the member 88 and hence the pawl 86 carried thereby, from the position shown in Figure 4 towards the position shown in Figure 8.

As the connector 86 is in latching engagement with the arm 85, the shifting member 75 will be moved against the action of its spring 79 in a direction for its arms 74 to co-act with the shoulders 73 of the shaft 31 in moving the handle O axially and inwardly of the door D, so as to enter the recess 33 in the latter and be releasably retained therein by snapping of the dogs 66 and 66a into the annular groove 71 of the handle, during the final closing movement of the door, all as shown in Figure 8.

During this movement of the door, the concurrent movement of the connector 86 from the position shown in Figure 4 to that shown in Figure 8, will cause the rounded end 91 of the connector to ride idly on the dwell portion 92 of the cam 94. However, when the door is in proximity to its fully closed position shown in Figure 2, the rounded end 91 of the connector strikes the active portion 93 of the cam, which swings the connector about the axis of its pivot pin 86 on the member 88 sufficiently for the bill 85 of the connector to clear the notch 84 of the latching arm 83 and thus free the latter from the connector, with the result that the spring 79 restores the shifting member 75 to its original position, all as clearly shown in Figure 9.

Although the operative connection between the door-controlled actuator 99 and the operating member O is now disrupted, the operating member remains latched in its non-operating position by the dogs 66 and 66a. To lock the door in its closed position, it is only necessary to turn the lock 57 to its locking position with the proper key, so as to rotate the locking lug 61 out of alignment with the slot 60 in the stop plate 53a, to lock the actuator 53 in its projected position against being manually pressed axially inward. The operating member O is inaccessible for turning in the recess 33, and there is thus no exposed means which can be tampered with to open the door.

To open the door, the lock 57 is unlocked by the proper key to restore the alinement of the locking lug 61 with the slot 60 in the stop plate 53a, following which inward pressure is manually exerted axially upon the actuator 53 so as to cause the cams 68 to co-act with the end of the dogs 66 and 66a engaged by the cams, in swinging the dogs oppositely about the axis of the pin 65 and against the action of the spring 67, sufficiently for the dogs to clear the annular groove 71 in the operating member O, thus rendering the spring 37 free to move the operating member axially outward and clear of the recess 33 to its projected and operating position shown in broken lines in Figure 2. Turning movement of the operating member can now be effected to retract the bolt B clear of the keeper K.

The door can be opened from the inside even though locked by the lock 57, as it is only necessary to actuate the inside handle I to retract the bolt B. It will be manifest that the operating member O can be manually moved to non-operating position when the door is open, should this mode of operation be desired.

It will also be appreciated that the other doors of the vehicle can be equipped with the above described mechanism embodying this invention so as to effect automatic movement of the outside handles of such doors to non-operating position in response to closing of the doors.

I claim:

1. In locking mechanism for closures, an operating member for the mechanism; means adapted to mount said member on the closure for movement to occupy operating and non-operating positions; means urging said member to operating position; means adapted to respond to closing movement of the closure to move the operating member to non-operating position; and means for releasably retaining the operating member in non-operating position.

2. In locking mechanism for closures, an operating member for the mechanism; means adapted to mount said member on the closure for movement to occupy operating and non-operating positions; means urging said member to operating position; means adapted to respond to closing movement of the closure to move the operating member to non-operating position; means for releasably retaining the operating member in non-operating position; and means for actuating said retaining means to release the operating member for movement by said urging means to operating position.

3. In locking mechanism for closures, an operating member for the mechanism; means adapted to mount said member on the closure for movement to occupy operating and non-operating positions; means urging said member to operating position; a closure-controlled actuator for the operating member; means operatively connecting said actuator to the operating member and adapted to respond to actuation of said actuator by closing movement of the closure, to move the operating member to non-operating position; means for disrupting said operative connection to the operating member when the closure is closed; means for releasably retaining the operating member in non-operating position; and manually operable means by which said retaining means can be actuated to release the operating member for movement by said urging means to operating position.

4. In locking mechanism for closures, an operating member for the mechanism; means

adapted to mount said member on the closure for movement to occupy operating and non-operating positions; means urging said member to operating position; means including an actuator adapted to co-act with a relatively fixed support in response to closing movement of the closure, to move the operating member to non-operating position when the closure is closed; and means for releasably retaining the operating member in non-operating position.

5. In locking mechanism for closures, an operating member for the mechanism; means adapted to mount said member on the closure for movement to occupy operating and non-operating positions; means urging said member to operating position; means including an actuator adapted to co-act with a relatively fixed support in response to closing movement of the closure, to move the operating member to non-operating position when the closure is closed; means for releasing the operating member from the last means when the operating member has been moved to non-operating position, so as to free the operating member for movement to operating position by said urging means; means for releasably retaining the operating member in non-operating position; and manually operable means for actuating said retaining means to release the operating member for movement by said urging means to operating position.

6. In locking mechanism for closures, an operating member for the mechanism; means adapted to mount said member on the closure for movement to occupy operating and non-operating positions; means including an operative connection to said operating member, by which the latter will be automatically moved to non-operating position in response to movement of the closure to closed position; and means for releasably retaining said member in non-operating position.

7. In locking mechanism for closures, an operating member for the mechanism; means adapted to mount said member on the closure for movement to occupy operating and non-operating positions; means including an operative connection to said operating member by which the latter will be automatically moved to non-operating position in response to movement of the closure to closed position; means co-acting with the last means to disrupt said operative connection to the operating member when the latter has been moved to non-operating position; and means for releasably retaining the operating member in non-operating position.

8. In locking mechanism for a hingedly mounted closure having a bolt; an operating member for the mechanism; means adapted to mount said member on the closure for movement axially to occupy operating and non-operating positions, and for rotation when in operating position to actuate the bolt; an actuator adapted to be movably mounted on the closure for co-action with a relatively fixed support during closing movement of the closure; and means operatively connecting said actuator to said operating member, by which the latter will be moved from operating to non-operating position in response to movement of the closure to closed position.

9. In locking mechanism for a hingedly mounted closure; an operating member for the mechanism; means adapted to mount said member on the closure for movement to occupy operating and non-operating positions; an actuator; means operatively connecting said actuator to said op-

erating member; and means adapted to co-act with said actuator in response to closing movement of the closure, to move the operating member from operating to non-operating position.

10. In locking mechanism for closures, an operating member having a shaft; means adapted to mount said member on the closure for rotation and for axial movement from operating to non-operating position; means urging the member axially to operating position; a closure-controlled actuator; means adapted to mount said actuator on the closure for movement; and means operatively connecting said actuator to said shaft, by which movement of the actuator to one position will move the operating member from operating to non-operating position.

11. In locking mechanism for closures, an operating member having a shaft; means adapted to mount said member on the closure for rotation and for axial movement from operating to non-operating position; means urging the member axially to operating position; an actuator; means adapted to reciprocably mount said actuator on the closure for engagement with the jamb of the closure to be moved thereby to one extreme position in response to closing of the closure; and means operatively connecting said actuator and shaft, by which movement of the actuator to said one extreme position will move the operating member from operating to non-operating position.

12. In locking mechanism for closures, an operating member having a shaft; means adapted to mount said member on the closure for rotation and for axial movement from operating to non-operating position; means urging the member axially to operating position; an actuator; means adapted to reciprocably mount said actuator on the closure for engagement with the jamb of the closure to be moved thereby to one extreme position in response to closing of the closure; means operatively connecting said actuator and shaft, by which movement of the actuator to said one extreme position will move the operating member from operating to non-operating position; means co-acting with said shaft to releasably retain the operating member in non-operating position; means for disrupting said operative connection between said shaft and actuator when the latter reaches said one extreme position; and a manually operable actuator operatively connected to said retaining means to release said shaft for movement and restore the operating member to operating position under the action of said urging means.

13. In locking mechanism for closures, an operating member having a shaft; means adapted to mount said member on the closure for rotation and for axial movement from operating to non-operating position; means urging the member axially to operating position; an actuator; means adapted to reciprocably mount said actuator on the closure for engagement with the jamb of the closure to be moved thereby to one extreme position in response to closing of the closure; a pivotally mounted shifting member normally urged in one direction to one extreme position; said shaft having means co-acting with said shifting member to be axially moved thereby during movement of the shifting member in the other direction; and means operatively connecting said shifting member to said actuator, by which movement of the latter to said one extreme position, will move the shifting member in said other direction to co-act with said shaft

in moving the operating member from operating to non-operating position.

14. In locking mechanism for closures, an operating member having a shaft; means adapted to mount said member on the closure for rotation and for axial movement from operating to non-operating position; means urging the member axially to operating position; an actuator; means adapted to reciprocably mount said actuator on the closure for engagement with the jamb of the closure to be moved thereby to one extreme position; said shaft having means co-acting with said shifting member to be axially moved thereby during movement of the shifting member in the other direction; means operatively connecting said shifting member to said actuator, by which movement of the latter to said one extreme position, will move the shifting member in said other direction to co-act with said shaft in moving the operating member from operating to non-operating position; said last means including disconnecting mechanism operable when the operating member reaches non-operating position, to disrupt the operative connection between the actuator and shifting member so as to permit the latter to return to its urged position; and means for releasably retaining the operating member in non-operating position when said operative connection is disrupted.

15. In locking mechanism for closures, an operating member having a shaft; means adapted to mount said member on the closure for movement to occupy operating and non-operating positions; means urging said member to operating position; an actuator; means adapted to mount said actuator on the closure for engagement with a relatively fixed support to be moved thereby to one position in response to closing of the closure; a pivotally mounted shifting member having a latching arm; means urging the shifting member rotatably to one extreme position; a connector; means movably mounting said connector for latching engagement with said arm and for movement to co-act with said arm in rotating the shifting member against its urging means; and means operatively connecting said last means to said actuator for movement by the latter to effect the aforesaid movement of said operating member to a position wherein the operating member will occupy non-operating position.

16. In locking mechanism for closures, an operating member having a shaft; means adapted to mount said member on the closure for movement to occupy operating and non-operating positions; means urging said member to operating position; an actuator; means adapted to mount said actuator on the closure for engagement with a relatively fixed support to be moved thereby to one position in response to closing of the closure; a pivotally mounted shifting member having a latching arm; means urging the shifting member rotatably to one extreme position; a connector; means movably mounting said connector for latching engagement with said arm and for movement to co-act with said arm in rotating the shifting member against its urging

means; means operatively connecting said last means to said actuator for movement by the latter to effect the aforesaid movement of said operating member to a position wherein the operating member will occupy non-operating position; means co-acting with said connector to move the latter out of latching engagement with the latching arm when the operating member has been moved to non-operating position, so as to permit the shifting member to return to its urged position; and means co-acting with said shaft to releasably retain the operating member in non-operating position.

17. In locking mechanism for closures, an operating member having a shaft; means adapted to mount said member on the closure for movement to occupy operating and non-operating positions; means urging said member to operating position; an actuator; means adapted to mount said actuator on the closure for engagement with a relatively fixed support to be moved thereby to one position in response to closing of the closure; a pivotally mounted shifting member having a latching arm; means urging the shifting member rotatably to one extreme position; a connector; means movably mounting said connector for latching engagement with said arm and for movement to co-act with said arm in rotating the shifting member against its urging means; means operatively connecting said last means to said actuator for movement by the latter to effect the aforesaid movement of said operating member to a position wherein the operating member will occupy non-operating position; a fixed cam having an active portion operable to move said connector out of latching engagement with said latching arm when the operating member has been moved to non-operating position; said shaft having a locking groove; locking dogs urged to engage said groove and releasably retain the operating member in non-operating position; and a manually operable actuator having means co-acting with said dogs to disengage the latter from said groove and free the operating member for movement to its operating position.

18. In locking mechanism for closures, an operating member for the mechanism; means adapted to mount said member on the closure for movement to occupy operating and non-operating positions; a manually operable actuator ring mounted for axial movement and urged to one extreme position; means co-acting with said operating member to releasably retain the latter in non-operating position; means co-acting with the last means and actuator ring, to release the last means from the operating member in response to axial movement of the actuator ring in opposition to its urging means; and a lock disposed in said actuator ring in a fixed position on said mechanism and having a rotatable locking lug; and a stop plate carried by said actuator ring and having an opening with which said locking lug is aligned or disaligned to accordingly free the actuator ring for axial movement or lock it against axial movement.

ALBERT J. LEONARD.
